(57) **CLAIM**

The ornamental design for a suspension for acoustic module, as shown and described.

DESCRIPTION

FIG. 1 is a perspective view of a suspension for an acoustic module showing my new design.

FIG. 2 is a top view of the suspension for the acoustic module.

FIG. 3 is a bottom view of the suspension for the acoustic module.

FIG. 4 is a front view of the suspension for the acoustic module.

FIG. 5 is a rear view of the suspension for the acoustic module.

FIG. 6 is a left view of the suspension for the acoustic module; and,

FIG. 7 is a right view of the suspension for the acoustic module.

The broken line portion of the figure drawings is included to show unclaimed subject matter only and forms no part of the claimed design.
